[57] CLAIM

The ornamental design for a removable vehicle top, as
shown and described.

DESCRIPTION

FIG. 1 is a top, rear perspective view of a removable
vehicle top showing my new design with the rear win-
dow in open condition;

FIG. 2 is a top plan view thereof with the rear window
in closed condition;

FIG. 3 is a side elevation view of FIG. 2, the opposite
side being a mirror image thereof;

FIG. 4 is a front elevation view of FIG. 2;

FIG. 5 is a rear elevation view of FIG. 2; and

FIG. 6 is a bottom plan view of FIG. 2.
